UNITED STATES PATENT OFFICE.

CHARLES S. LABOFISH, OF WASHINGTON, DISTRICT OF COLUMBIA, ASSIGNOR TO UNION TYPEWRITER COMPANY, OF JERSEY CITY, NEW JERSEY, A CORPORATION OF NEW JERSEY.

TABULATING DEVICE FOR TYPE-WRITERS.

No. 901,973.

Specification of Letters Patent.

Patented Oct. 27, 1908.

Application filed March 30, 1901. Serial No. 53,670.

To all whom it may concern:

Be it known that I, CHARLES S. LABOFISH, a citizen of the United States, residing at Washington, in the District of Columbia, have invented certain new and useful Improvements in Tabulating Devices for Type-Writers; and I do hereby declare the following to be a full, clear, and exact description of the invention, such as will enable others skilled in the art to which it appertains to make and use the same.

My invention relates to improvements in tabulating mechanism for typewriters, and the objects of my invention are, first, to produce a neat, simple and compact tabulating mechanism fitted to the typewriter in such a manner as to conceal it entirely from view, thereby obviating the usual objections to tabulating attachments which encumber the machine, and detract from the appearance thereof; second, to so construct the tabulating device as to enable the operator to bring a column or columns into vertical alignment by the manipulation of the numbered typewriter or printing keys, thereby dispensing with the auxiliary keys usually employed to accomplish the results; third, to provide a very simple and efficient carriage-release; and fourth, to provide easily adjustable and removable column stops which are readily accessible to the operator.

To the above and other ends which will hereinafter appear, my invention consists of the features of construction, arrangements of parts and combinations of devices set forth in the following specification and particularly pointed out in the appended claims.

In the accompanying drawings wherein like reference characters indicate corresponding parts in the various views, Figure 1 is a vertical front to rear sectional view of a typewriter embodying my invention; parts unnecessary to an understanding of my invention being omitted from this view. Fig. 2 is a plan view of a portion of the traveling typewriter carriage. Fig. 3 is a plan view with parts broken away showing portions of the tabulating mechanism and the associated parts. Fig. 4 is a detail vertical sectional view taken on the line X—X of Fig. 3. Fig. 5 is a detail perspective view of the shift key and combined shifting and locking device. Figs. 6, 7, 8 and 9 are detailed views of the parts entering into the construction of my tabulating device.

Similar letters and figures refer to similar parts throughout the several views.

In the drawings, A indicates the lower portion of the typewriter frame; B, the upper front portion thereof; C, the front part of the traveling paper carriage which carries a cylindrical platen in the usual manner; D, a rod running parallel with the carriage upon which the supporting roller E, indicated by the dotted lines, bears; F, indicates two lugs attached to the hood in which the roller E is housed; G, designates the numbered typewriter or printing keys; H, a spacing or feed dog; I, the rack, and K, the typewriter scale. The above parts of the typewriter operate in conjunction with my tabulating device, as will be hereinafter described.

A rock shaft or stop rod 10 extends in the direction of the travel of the carriage and has a longitudinal groove 11, and is held rotatable in the upper front portion of the typewriter frame B, close to, and parallel with the rod D, upon which the roller E, bears. A stop rod 12, T-shaped in its cross section, and having a series of transverse notches 13 cut therein, is rigidly secured in the upper portion of the typewriter frame adjacent to the rod or rock shaft 10, and parallel therewith. A hollow graduated contact piece 15, is fitted between the lugs F to slide upon the rod 10, and is prevented from turning thereon by a pin 16, which engages the longitudinal groove 11. The said contact piece consists of a raised spiral 17 which covers about eight-tenths of the periphery of the sleeve, 90 leaving a space 18 of about two-tenths bare (for purposes to be hereinafter described) and notches are cut upon the said raised spiral so as to form a series of segmentally and spirally arranged steps 19, as shown in Fig. 6 which constitute denominational stops.

Column stops 20 are recessed and shaped to fit the T-shaped stop rod 12 referred to above, and are fitted to slide freely thereon. These column stops are each formed with projections 21, extending toward the spirally arranged stops and with ears 22 to which are hinged U-shaped twin cams 23, provided with a handle 24 wherewith the said cams are operated to engage the notches 13 so as to lock the column stop 20 securely in position at any point on the rod 12, as clearly shown in Figs. 2 and 7.

A socket 26 is detachably secured to the lower right hand side of the typewriter frame 110

by a screw 27 and a bracket 28 is likewise detachably held by screws 29 to the lower portion of the typewriter frame just opposite the said socket 26. A rock shaft 30, formed 5 with rockers 31 and heels 31^a, constitutes a frame which is mounted to rock in the bearings of the said socket and bracket and has also a slight lateral movement therein against the tension of the spring 32 in the socket 26, 10 as shown in Figs. 3 and 4.

To the rock shaft 30 is secured a cross bar 33 which is in the nature of crank arms that project in opposite directions from the rock shaft and in effect constitute a lever of which 15 the rock shaft is the fulcrum. A segment 34 is pivotally mounted upon the upper portion B of the typewriter frame and the said segment is provided with a short arm 35 which is linked to the forward arm of the lever or 20 cross bar 33 by a connecting rod 36 so that when the shaft 30 is rocked the segment is actuated in relative proportion thereto. A pinion 37 is secured to the rod or rock shaft 10 and meshes with the segment, as clearly 25 shown in Fig. 1.

The extreme rear end of the cross bar or lever 33 is provided with a mutilated segment 40 which is in constant mesh with a pinion 41 secured upon a rock shaft 42 disposed 30 parallel with the rock shaft 30. A short arm 43 projects from the shaft 42, and this arm is linked by a connecting wire 46 to a lug or pin 45 which projects from the spacing dog H as is clearly shown in Fig. 1.

Within the L-shaped bracket 28 is a combined shifting and locking device which has a cam 50, a curved top or hook-like locking portion 51 and guide pins 52, which guide pins bear in openings in the bracket so that the 40 cam has a vertical movement in the bracket 28. A shift key 54 is pivotally mounted in the lower portion of the type-writer frame at 53, and has an enlarged cupped out end 55 which is just beneath, and co-operates with, 45 the lower end of one of the guide pins 52 which extends lower than the other or others, as clearly shown in Figs. 3 and 5.

In operating this tabulating device to bring a column or columns into vertical-alinement, the open column stops 20 are first placed upon the stop rod 12, by pushing them over the recess 14, and then moving each of them to the point upon the scale K where the decimal point will appear in the 50 respective printed column. The handles 24 are then pulled downward so that the twin cams 23 enter the notches 13 opposite the cams and lock the column stops securely in position; the backs 25 which connect the two 55 cams 23 impinging against the rod 12 prevent the cams from coming out of engagement with the rod by the jarring of the machine.

In operating the machine we will now suppose that it is desired to print the sum of

500.00 beneath an amount already printed; the shift key 54 is depressed and the cam 50, which is normally held downward by the spring 56, is thereby forced upward, releasing the locking portion 51 from engagement 70 with the shaft and shifting the rock shaft 30 longitudinally toward the right and bringing the rockers 31 beneath the extensions 38 of the numbered typewriter keys. The typewriter or printing key bearing the numeral 75 "5" which key ordinarily is employed to print the numeral "5" is then depressed, the extension 38 on its lever bearing upon the rocker 31 beneath said lever, causing the rocker to incline until the heel 31^a touches 80 the extension, thus preventing the lever from going further and arresting it at a point where the movement transmitted thereto is ineffective to throw the associated type bar to the printing point, thereby preventing 85 an imprint by the actuation of the printing key. It is at this time that the numeral printing keys may be used as tabulator keys. The dip thus imparted to the rocker moves the forward arm of the lever 33 90 downwardly and the segment 34 which is connected to the lever is moved, say a distance corresponding to four teeth of the segment. This movement is effective to turn the rock shaft 10 a corresponding distance or 95 four-tenths of a revolution, thereby moving the denominational stops in a direction transverse to the travel of the carriage, bringing the fourth spiral step or denominational stop 19 in line with the column stop projection 21. A downward movement of the fore part of the lever 33 causes its rear end to rise a corresponding distance and the latter, having the mutilated segment 40 secured thereto moves the mutilated pinion 41 until the 105 untoothed portion of the segment 40 engages the mutilated portion of the pinion 41. The slight turn which the pinion 41 makes is effective to tilt the short arm 43, which is connected to the dog H, a distance sufficient to 110 pull down and to disengage the dog H from the rack I. This disengagement of the dog from the rack releases the carriage which, by the tension of its main spring, is pulled forward or towards the left until the properly 115 positioned spiral step or denominational stop 19 is brought into contact with the column stop projection 21, thus arresting the carriage to start writing "500.00" at the proper denominational position within the 120 proper columnar field. Pressure on the shift key is now released, the feed rack is reengaged by the dog H and the carriage remains five spaces before the hundredths position, so that after the sum of 500.00 is printed the 125 figures in the units, tens and other positions will be in vertical alinement with the figures in the corresponding positions in the column already printed. The same operation is repeated throughout in the column or columns. 130

Thus, when the typewriter or printing key bearing the numeral "2" is struck to bring the carriage to stop at the decimal point, and when the numeral key "3" is actuated it is effective to stop the carriage at the units point and when the "4" key is actuated it arrests the carriage at the tens point position and so on. The effect of depressing the different numeral keys when the shift key 54 is depressed is, as heretofore pointed out, to turn the set of denominational stops 19 a distance corresponding to the denomination represented by the key depressed. As the pressure on the shift key is released the rock shaft 30 is forced to the left, thus carrying the members or projections 31 and 33 thereon out of the path of the key extensions 38, and the numeral key levers are thus allowed to play freely in the spaces between said projections.

When the tabulator is in operation and pressure upon the typewriter numeral key is released, the segment 34 which has been pulled forward against the tension of the spring 36' by the depression of the actuated key, is returned to its normal position, bringing the bare portion 18 between the terminal denominational stops in line with the projections 21 of the column stops, so that the graduated stop member 15 can pass the projections 21 freely without touching them. By spacing the adjacent denominational stops apart as shown the column stops may be received in the interdental spaces between denominational stops as the latter are moved to and from operative position, the stops passing one another freely in a vertical plane fore and aft of the machine or in a direction transverse to the travel of the carriage so that column stops do not interfere with the free return of the denominational stops to normal position.

To reduce the jar which is caused by the released carriage striking against the column stops, a yielding cushion 15', which may be soft rubber or a spring, is interposed between the graduated contact piece 15 and the guide lugs F, as is clearly shown in Fig. 2.

Certain of the features disclosed in the present case are claimed more broadly in my application, Serial No. 42,676, filed January 9th, 1901, the claims in the present case being restricted to features not embodied in said earlier application.

55 What I claim as new and desire to secure by Letters Patent, is:—

1. In a tabulating attachment for typewriting machines, the combination with the fixed frame of the machine, of printing keys, a transversely movable paper carriage, a rock shaft extending transversely of the machine and in operative relation to the printing keys and adapted to be rocked different degrees by the depression of said keys, a rotary shaft, a graduated contact piece carried

thereby, connections including a segment between said rock shaft and said rotary shaft, a connection between said graduated contact piece and the typewriter carriage, and one or more relatively fixed column stops. 70

2. In a tabulating attachment for typewriting machines, the combination of a transversely arranged rock shaft as 30, a series of graded rockers thereon, a series of printing keys provided with extensions to engage said rockers to turn the shaft 30 different degrees, a second transversely extending rock shaft, operative connections between said rock shafts, a graduated contact piece upon said second rock shaft adapted to be turned different degrees, and column stops. 75

3. In a tabulating attachment for typewriting machines, the combination with the fixed frame, of printing keys, a transversely movable paper-carriage, a shiftable rock-shaft extending transversely of the machine beneath the printing keys and operable thereby, suitable column stops, a rock shaft carrying a contact piece adapted to engage 90 said column stops to arrest the said carriage at a predetermined point, and an operative connection between the said two rock-shafts. 85

4. In a typewriting machine, the combination of the carriage, a feeding mechanism 95 therefor, a rock shaft, means for rocking said shaft, a toothed segment attached to said shaft, an additional rock shaft, a pinion thereupon and engaging said segment, and operative connections between said last mentioned 100 rock shaft and the carriage feeding mechanism whereby when the first mentioned rock shaft is actuated the parts of the carriage feeding mechanism may be separated and the carriage released. 105

5. In a tabulating attachment for typewriting machines, the combination of a paper carriage, a feeding mechanism therefor, printing keys, a rock-shaft arranged beneath the printing keys and operable thereby, 110 mechanism adapted to release the paper carriage operated by said rock shaft, column stops adjustably secured against movement to the frame of the machine, and means operatively connected with said rock shaft and 115 movable thereby into coöperation with the column stops for arresting the carriage at a predetermined point.

6. In a typewriting machine and tabulating mechanism, the combination of a carriage, a tabulating stop, segmentally and spirally arranged denominational stops which are spaced apart to permit the tabulating and denominational stops to pass one another in a transverse direction, there being 120 a space between the terminal denominational stops to permit a free longitudinal movement of the denominational and tabulating stops past one another during the travel of the carriage when the tabulating mechanism is not 125 130

in operation, and means for interposing one of said tabulating and denominational stops in the path of the other.

7. In a typewriting machine, the combination of a row of printing keys, a pivoted lever adapted to be operated by any one of said keys, and having a rack connected therewith, a pinion operated by said rack, and a carriage stop controlled by said pinion.

10. 8. In a typewriting machine, the combination of printing keys, a pivoted lever adapted to be operated by any one of said keys, and having a rack operatively connected to one end, a pinion operated by said rack, and a denominational selecting stop-member controlled by said pinion and moved different distances by said keys.

9. In a typewriting machine and tabulating mechanism, the combination of printing keys, a carriage, a series of segmentally arranged denominational stops, a tabulating stop which is adapted to coöperate with the denominational stops to arrest the carriage, and means under control of the printing keys 20 for turning the series of denominational stops and tabulating stops one relatively to the other.

10. In a typewriting machine and tabulating mechanism, the combination of printing keys, a carriage, a series of segmentally arranged denominational stops, a tabulating stop which is adapted to coöperate with the denominational stops to arrest the carriage, means under control of the printing keys for 30 turning the series of denominational stops and the tabulating stop relatively one to another, and means controlled by said turning means for releasing the carriage.

11. In a typewriting machine and tabulating mechanism, the combination of printing keys, a carriage, a tabulating stop, denominational stops which are spaced apart to provide a free movement of the tabulating and denominational stops past one another, 40 and means under control of said printing keys for bringing the stops into coöperative relation.

12. In a typewriting machine and tabulating mechanism, the combination of a carriage, a tabulating stop on the frame of the machine, a series of spirally arranged denominational stops which moves with the carriage, printing keys, a universal frame, means connected with said frame to move 50 said denominational stops, and means for variably moving the universal frame by said printing keys.

13. In a typewriting machine and tabulating mechanism, the combination of a carriage, a tabulating stop, a series of spirally arranged denominational stops, a plurality 60 of printing key levers for effecting a relative movement to different positions between the tabulating and denominational stops, a rock-ing universal frame also-operated by said

printing key levers, and means connected to said frame for releasing the carriage.

14. In a typewriting machine and tabulating mechanism, the combination of printing keys, a carriage, rotatable denominational stops, means controlled by said printing keys for rotating said denominational stops to bring them in different denominational positions, a coöperating tabulating stop, and means for releasing the carriage when said 70 denominational stop is rotated.

15. In a typewriting machine and tabulating mechanism, the combination of printing keys, a carriage, a stop bar which extends in the direction of the travel of the carriage, a plurality of denominational stops carried by 80 said stop bar, a coöperating column stop fixed on the frame of the machine, means under control of said printing keys for bringing the denominational stops into operative 85 positions and for arresting the carriage at the proper denominational position as determined by the particular denominational stop that is brought into operation, and means for releasing the carriage when the 90 denominational stop is moved to the operative position.

16. In a typewriting machine and tabulating mechanism, the combination of a carriage, a rock shaft which extends in the direction of the travel of the carriage, a plurality of denominational stops carried by 95 said rock shaft and located at different points around the same, a tabulating stop which coöperates with the denominational stop, 100 said tabulating and denominational stops being adjustable relatively one to another, and means under control of the printing keys for rocking said rock shaft.

17. In a typewriting machine and tabulating mechanism, the combination of a carriage, a rock shaft which extends in the direction of the travel of the carriage, a plurality of segmentally arranged denominational stops carried by 110 said rock shaft, a column stop which coöperates with the denominational stops, printing keys, means under control of the printing keys for rocking said rock shaft, and means for releasing the carriage when the rock shaft actuating means are 115 operated.

18. In a typewriting machine and tabulating mechanism, the combination of a carriage, radially and segmentally arranged denominational stops, a coöperating column 120 stop, printing keys, means under control of the printing keys for moving the denominational stop to coöperate with the column stop to arrest the carriage, and means for releasing the carriage when the stops are 125 moved into coöperative relation.

19. In a typewriting machine and tabulating mechanism, the combination of a power-driven carriage, a plurality of spirally arranged denominational stops, printing keys, 130

and means under control of said printing keys for moving said denominational stops to different extents transversely of the travel of the carriage to arrest it at different denominational positions, a coöperating tabulating stop, and means for releasing the carriage when said stops are brought into co-operative relation.

20. In a typewriting machine and tabulating mechanism, the combination of a power-driven carriage, a plurality of denominational stops, a fixed coöperating tabulating stop, a plurality of printing keys for moving the denominational stops to different extents transversely of the travel of the carriage, and means for releasing the carriage when said denominational stops are actuated.

21. In a typewriting machine and tabulating mechanism, the combination of a power driven carriage, a tabulating stop, a rock shaft, denominational stops carried by said rock shaft, a pinion on said rock shaft, a rack which meshes with said pinion, printing keys, means under control of said printing keys for moving said rack to different extents to bring different denominational stops into coöperation with the tabulating stop, and means for releasing the carriage when said means under the control of the printing keys are actuated.

22. In a typewriting machine and tabulating mechanism, the combination with the fixed frame of the machine, and a movable paper carriage, of stop devices embodying a

graduated contact piece moving with the paper carriage, and a suitable stop coöperating thereby to arrest the same at different denominational positions, printing keys, and means under control of said printing keys 40 and coöperating with said graduated contact piece and with the escapement mechanism of the machine for releasing the paper carriage and adjusting the graduated contact piece to arrest the carriage at the desired denominational position by a single operation of a printing key.

23. In a typewriting machine and tabulating mechanism, the combination with a fixed frame of the machine and a movable carriage, of stop devices embodying a graduated contact piece moving with the carriage, a plurality of column stops adjustably secured to the fixed frame of the machine and coöperating with the graduated contact 55 piece to arrest the carriage at different denominational positions in successive columns, and a plurality of printing keys coöperating with said graduated contact piece and with the escapement mechanism of the 60 machine for releasing the carriage and arresting it at the desired denominational positions in successive columns.

In testimony whereof I affixed my signature, in presence of two witnesses.

CHARLES S. LABOFISH.
